(57) **CLAIM**

The ornamental design for a child-resistant storage case, as shown and described.

DESCRIPTION

FIG. 1 is a top plan view of a child-resistant storage case showing our new design.

FIG. 2 is a front elevational view thereof.

FIG. 3 is a rear elevational view thereof.

FIG. 4 is a left side elevational view thereof, with the right side elevational view being a mirror image of FIG. 4.

FIG. 5 is a bottom plan view thereof.

FIG. 6 is a top axonometric view thereof.

FIG. 7 is a front elevational view of an alternative embodiment of the child-resistant storage case.

FIG. 8 is a rear elevational view thereof corresponding to FIG. 7.

FIG. 9 is a left side elevational view thereof, with the right side elevational view being a mirror image of FIG. 9; and, FIG. 10 is a top axonometric view thereof corresponding to FIGS. 7-9.

1 Claim, 8 Drawing Sheets
